DESIGN FOR A WATCH BRACELET OR THE LIKE

La Roy E. Pitman, Attleboro, Mass., assignor to Pitman & Keeler, Attleboro, Mass., a partnership of La Roy E. Pitman and Lawrence P.
Keeler

Application July 14, 1939, Serial No. 86,019

Term of patent 7 years

To all whom it may concern:

Be it known that I, La Roy E. Pitman, a citizen of the United States, residing in the city of Attleboro, county of Bristol, and Commonwealth of Massachusetts, have invented a new, original, and ornamental Design for a Watch Bracelet or the Like, of which the following is a specification, reference being had to the accompanying drawing, forming a part thereof, in which:

Fig. 1 is a plan view of a watch bracelet showing my new design;

Fig. 2 is an edge view of the same; and
Fig. 3 is a bottom plan view of the watch bracelet.

The essential feature of my design resides in the specific chain links on opposite ends of the bracelet in combination with the central expandible link portion.

I claim:

The ornamental design for a watch bracelet or the like, substantially as shown and described.

LA ROY E. PITMAN.
